(57) **CLAIM**

The ornamental design for a top of a rocker switch and lens, as shown and described.

DESCRIPTION

FIG. 1 is an isometric view of a top of a concave circular rocker switch with a textured clear lens;

FIG. 2 is a left side elevation of the rocker switch top in FIG. 1;

FIG. 3 is a front elevation view of the rocker switch top in FIG. 1;

FIG. 4 is a right side elevation of the rocker switch top in FIG. 1;

FIG. 5 is a rear elevation view of the rocker switch top in FIG. 1;

FIG. 6 is a top view of the rocker switch top in FIG. 1;

FIG. 7 is a bottom view of the rocker switch top in FIG. 1;

FIG. 8 is an isometric view of a top of a concave circular rocker switch with a clear lens;

FIG. 9 is a left side elevation of the rocker switch top in FIG. 8;

FIG. 10 is a front elevation view of the rocker switch top in FIG. 8;

FIG. 11 is a right side elevation of the rocker switch top in FIG. 8;

FIG. 12 is a rear elevation view of the rocker switch top in FIG. 8;

FIG. 13 is a top view of the rocker switch top in FIG. 8; and,

FIG. 14 is a bottom view of the rocker switch top in FIG. 8. The broken lines are for illustrative purposes only and form no part of the claimed design.
